CLAIM

The ornamental design for a Star of David cross, as shown and described.

DESCRIPTION

FIG. 1 is a top, front, left perspective view of a Star of David cross showing my new design;

FIG. 2 is a front elevational view thereof;

FIG. 3 is a bottom view thereof;

FIG. 4 is a top plan view thereof;

FIG. 5 is a left side elevational view thereof; and,

FIG. 6 is a right side elevational view thereof.

The items shown in broken lines are depicted for illustrative purposes only and form no part of the claimed design.
